UNITED STATES PATENT OFFICE.

JAMES B. HARRINGTON, OF NORFOLK, VIRGINIA.

DESIGN FOR A STATUETTE.

Application filed March 20, 1923. Serial No. 5,547. Term of patent 3½ years.

To all whom it may concern:

Be it known that I, JAMES B. HARRINGTON, a citizen of the United States, residing at Norfolk, in the county of Norfolk and State of Virginia, have invented a certain new, original, and ornamental Design for a statuette, of which the following is a specification, reference being had to the accompanying drawing, forming part thereof.

I claim:

The ornamental design for a statuette as shown.

JAMES B. HARRINGTON.
